UNITED STATES PATENT OFFICE.

GUSTAVE E. MESCHKE, OF MEDORA, NORTH DAKOTA, ASSIGNOR OF ONE-THIRD TO J. B. CHAUSSEE AND ONE-THIRD TO H. A. MACKOFF, BOTH OF DICKINSON, NORTH DAKOTA.

AUTOMOBILE RADIATOR.

Application filed October 6, 1924. Serial No. 742,015.

To all whom it may concern:

Be it known that I, GUSTAVE E. MESCHKE, a citizen of the United States, residing at Medora, in the county of Billings and State 5 of North Dakota, have invented certain new and useful Improvements in Automobile Radiators, of which the following is a specification.

My invention relates to improvements in 10 radiators for automobiles.

An important object of the invention is to provide a radiator of the above mentioned character, formed in parts which may be readily assembled and disconnected, 15 whereby the device may be properly repaired, when necessary.

Further object of the invention is to provide a radiator of the above mentioned character so constructed that the liability of 20 leakage is reduced to the minimum.

Further object of the invention is to provide an automobile radiator which is strong, durable, and possesses a large radiating capacity.

Other objects and advantages of the invention will be apparent during the course 25 of the following description.

In the accompanying drawings forming 30 a part of this specification and in which like numerals are employed to designate like parts throughout the same,

Figure 1 is a front elevation of a radiator embodying my invention,

Figure 2 is a side elevation of the same, 35 Figure 3 is a horizontal section taken on line 3—3 of Figure 1,

Figure 4 is vertical section taken on line 4—4 of Figure 3,

Figure 5 is a transverse vertical section 40 taken on line 5—5 of Figure 4,

Figure 6 is a perspective view of one of the supporting members, and,

Figure 7 is an enlarged detail section 45 through the upper end of one of the tubes, and associated elements.

In the drawings, wherein for the purpose of illustration is shown a preferred embodiment of my invention, the numeral 10 designates an upper tank, provided with an outlet coupling 11, projecting laterally from 50 its inner side. This coupling is connected with the top of the water jacket, in any well known manner. The tank 10 is also provided in its top with a filling neck 12,

equipped with a cap 13, detachable therefrom. The tank 10 is provided at its lower end with a marginal outwardly extending horizontal flange 14, engaging the top of a bottom-plate 15. This bottom-plate has its inner portion transversely thickened, the 60 same rising upwardly, as shown, to strengthen the same. Arranged beneath the bottom-plate 15 is a compression-plate 16.

The numeral 17 designates a bottom tank provided at its top with a marginal outwardly extending horizontal flange 18, engaging the lower face of a top-plate 19, the inner portion of which is thickened, and projects downwardly, as shown, to strengthen the same. Arranged near and above the top-plate 19 is a lower compression-plate 20, as shown.

The numeral 21 designates a pair of side supporting members, which are preferably formed of a suitably stiff sheet metal. These side supporting members are U-shaped in horizontal cross section, and are provided upon their bases 22, with outwardly bulging longitudinal pockets 23. At their upper and lower ends, the side supporting members 21 have horizontal flanges 24, integral therewith, which engage with the lower and upper faces of the compression-plates 16 and 20, as shown.

In connection with the upper tank 10, the flange 14, bottom-plate 15, compression-plate 16, and flange 24, are all clamped together by bolts or rivets 24', passing through openings formed therein, and steel washers 25, preferably surround the bolts 24', between the bottom-plate 15 and the compression-plate 16. Between the flanges 24 of the side supporting members 22, the flange 14 of the upper tank, the bottom-plate 15, and compression-plate 16 are connected by bolts 90 or rivets 25', passing through openings therein, and through washers 26, such as steel washers.

In connection with the lower tank 17, the lower flange 24, compression-plate 20, and flange 18 are all connected by clamping bolts or rivets 26', passing through openings formed therein, and through steel washers 27. Between the side supporting members, the flange 24, compression-plate 20, top-plate 19, and flange 18, are connected by bolts 28 or the like, passing therethrough, and through steel washers 29. By this means

2
the top and bottom tanks are securely rigidly connected.

The lower tank 17 is provided with an intake coupling 30, for connection with the bottom of the water jacket of the engine. The tank is also equipped with a drain cock 31, as is customary.

The bottom-plate 15 is provided with transverse rows of vertical openings 32, which discharge at their upper ends into the top tank, and lead at their lower ends into recesses 33. These recesses have inner tapered walls 34, and outer or lower vertical cylindrical walls 35 affording stop shoulders. The upper compression-plate 16 is provided with cylindrical vertical openings 36, which lead at their upper ends into recesses 37. These recesses have lower tapered walls 38, and upper vertical cylindrical walls 39, forming stop shoulders. The recesses 37 are in alinement with the recesses 33, and are adapted for the reception of rubber gaskets 40, shaped to fit therein, and having intermediate flanges 41, projecting outwardly beyond these recesses, to be confined between the bottom-plate 15 and compression-plate 16.

The lower compression-plate 20 is provided with transverse rows of vertical cylindrical openings 42, which lead at their lower ends into recesses 43. These recesses have upper tapered walls 44, and lower cylindrical vertical walls 45, forming stop shoulders. The top-plate 19 has vertical openings 46 formed therein, which lead at their upper ends into recesses 47, having lower inclined walls 48, and upper vertically cylindrical walls 49, forming stop shoulders. The numeral 50 designates rubber gaskets, properly shaped for insertion within the recesses 43 and 47, and are equipped with intermediate flanges 51, projecting outwardly beyond these recesses and confined between the top-plate 19 and compression-plate 20.

These rubber gaskets 40 and 50 are adapted to snugly receive the water circulating tubes 52, which may be formed of copper, such tubes also passing through the openings and recesses associated with these gaskets, as is obvious. The lower ends of these tubes lead directly into the lower tank 17, while the upper ends of the tubes are provided with outwardly spun flanges 53, Figure 7, which are adapted to engage within the inclined tops of the recess 33. The openings 32, are in alinement with these tubes, as shown.

The upper compression-plate 16 is preferably provided with reinforcing and radiating fins 54, integral therewith, and depending therefrom, while the lower compression-plate 20 is provided upon its upper face with reinforcing and radiating fins 55, integral therewith. Arranged between the fins 54 and 55, are spaced horizontal radiating

fins 56, formed of thin copper sheets or the like, apertured for receiving the tubes 52, and projecting into the side supporting members 22. These fins 56 may be held upon the tubes in spaced relation, by any suitable means.

The numeral 57 designates an overflow pipe, the upper end of which leads into the filling neck 12. This overflow pipe extends downwardly through openings 58 and 59, and passes through a rubber gasket 60, similar to the gasket 40 and held in a similar manner within recesses. This overflow pipe also passes through a lower gasket 61, similar to the gasket 50 and held between the compression-plate 20 and top-plate 19 in a similar manner. The lower end of this overflow pipe leads downwardly through the flange 18 of the bottom tank 17, and discharges to the exterior thereof. The overflow pipe 57 may be flexible, and may be formed of copper or the like, and it is preferably arranged within the outwardly bulging recess 23. The recess 23 in the other side supporting member is formed to make the device appear symmetrical.

In view of the foregoing description, it will be seen that when the upper tank 10 and its bottom-plate 15 are removed from the lower compression-plate 16, that the tubes 52 may be moved longitudinally within their gaskets, so that they may be removed and new tubes substituted. When the bolts are screwed up, the gaskets are placed under compression and binding 100 against the tubes affect a water tight joint. The vertical shoulders of the recess holding the gaskets prevent them from spreading laterally when heated.

It is to be understood that the form of my invention herewith shown and described, is to be taken as a preferred example of the same, and that various changes in the shape, size, and arrangement of parts, may be resorted to without departing from the spirit 110 of my invention or the scope of the subjoined claim.

Having thus described my invention, I claim:

In an automobile radiator, an upper tank, 115 a bottom-plate for the same having openings and recesses leading into the openings, a lower compression-plate disposed near and beneath the bottom-plate and having openings and recesses leading into such openings, elastic washers having their upper and lower ends leading into said recesses, heat radiating and reinforcing ribs formed upon the lower compression-plate, a lower tank, 120 a top-plate for the lower tank having openings and recesses leading into the same, an upper compression-plate having openings and recesses leading into the same, elastic washers having their upper and lower ends 125 held within the last named recesses, heat 130

radiating and reinforcing fins formed upon the upper compression-plate, tubes extending through the washers and provided at their upper ends with outwardly projecting flanges engaging over the upper washers, side supporting members arranged between the upper and lower compression plates and having outwardly extending upper and lower flanges and outwardly bulging longitudinal recesses, bolts clamping the adja-

cent elements to the upper and lower flanges, and an overflow pipe extending through the bottom-plate and adjacent lower compression-plate and the top-plate and its adjacent upper compression-plate and having a part 15 thereof arranged within the outwardly bulging recess of the adjacent side supporting member.

In testimony whereof I affix my signature.
GUSTAVE E. MESCHKE.
